Primary Examiner—Mitchell Siegel*(74) Attorney, Agent, or Firm*—Richard J. Gurak; Welsh & Katz Ltd.(57) CLAIM

The ornamental design for a golf club putter head weight, as shown and described.

DESCRIPTION

FIG. 1 is a front perspective view of the golf club putter head weight;

FIG. 2 is a rear perspective view thereof;

FIG. 3 is a top view thereof;

FIG. 4 is front view thereof; and,

FIG. 5 is rear view thereof.

The broken away section of the putter head weight is shown due to indeterminate length.
